UNITED STATES PATENT OFFICE.

ADOLPH E. FEIGE, OF HACKENSACK, NEW JERSEY, ASSIGNOR TO UNIVERSAL INDUSTRIAL CORPORATION, OF HACKENSACK, NEW JERSEY, A CORPORATION OF DELAWARE.

DESIGN FOR A DISPLAY STAND FOR HOSE CLAMPS.

Application filed October 19, 1922. Serial No. 4,027. Term of patent 3½ years.

To all whom it may concern:

Be it known that I, ADOLPH E. FEIGE, a citizen of the United States, residing at Hackensack, in the county of Bergen and State of New Jersey, have invented a new, original, and ornamental Design for a Display Stand for Hose Clamps, of which the following is a specification, reference being had to the accompanying drawing, forming part thereof.

In the drawing the figure is a front elevation of a display stand for hose clamps, showing my new design.

I claim—

The ornamental design for a display stand for hose clamps, as shown.

ADOLPH E. FEIGE.
